SASH HANGER

Filed Aug. 11, 1947

FIG. 1

FIG. 3

FIG. 2 INVENTOR
EUGENE F. BARBER

BY *Canwell & Lagard*
ATTORNEYS

ment of the said rail along the rest 31. This surface merges with another surface 35 which recedes from the surface 33. The opposite side of the supporting member 29 is provided with an abutment 37 which has a surface 38 adapted to engage the upper portion of the side 19 of the rail 18 of sash 15a. This abutment terminates intermediate the ends of the supporting member 29 and the said surface merges with another surface 39 which forms a continuation of the surface 38 and recedes therefrom. The supporting member 29 being constructed similarly to the supporting member 29a, it will readily be seen that the opening 34 is formed partly by the surfaces 33 and 35 of the supporting member 29a and partly by the surfaces 38 and 39 of the supporting member 29. By means of the arrangement of the surfaces 33, 35, 38 and 39, an enlargement 36 is formed in the opening 34 at the upper end of the same, and also an enlargement 41 at the lower end thereof. The said surfaces are so constructed that a recess 42 is also formed in the surface 39 which serves a purpose to be presently described. By means of the construction utilized the opening 34 is formed with two sections 43 and 44. The section 43 runs vertically between the surfaces 37 and 33 and the section 36 extends obliquely between the surfaces 35 and 39.

In order to increase the area of the various surfaces of the supporting members 29, 29a and 29b, etc., a flange 45 is struck out of the material from which the hanger is formed and which flange extends completely around the said supporting members and also about the openings 34, etc. This construction also greatly stiffens the entire hanger and increases the weight of the load which may be carried thereby.

The method of using the invention is as follows: The screen sash or storm sash as the case may be, is first held in inclined position and then inserted into the section 44 of the opening 34, the sash being first applied to the opening 34 at the enlargement 41 therein. When the sash is so arranged the rail 18 clears the rest 31. The sash is then slid along said section of the opening until it becomes received in the enlargement 36 at the opposite end of the same. The parts then become arranged as indicated in connection with the sash 15, in Fig. 2. It will be noted that in this position the under surface 22 of the rail 18 is above the rest 31 and molding 24 is in recess 42. The sash may now be swung from an inclined position to a vertical position and after reaching such position the sash may be lowered until the surface 22 engages the rest 31. The parts then become arranged relative to one another as indicated in connection with the sash 15a as shown in Fig. 2. When so disposed the surface 22 engages the rest 31 while the surface 38 of an abutment 37 engages the upper portion of the side 19 of rail 18. At the same time the surface 33 of the stop 32 lies parallel to the side 21 of the rail 18. This surface limits the movement of the rail 18 inwardly along the rest 31 and prevents the said rest from engaging the screen or the glass of the sash. The sash then become securely supported by the hanger and cannot be displaced without the swinging of the same to the angle shown in conjunction with the sash 15. Upon removal of the sash the reverse procedure is adopted.

I have referred to the structure carried by the hanger in this specification and claims as a sash. It will be readily comprehended that the term so used embraces storm sash, screen sash, screen

windows or any other type of sash or similar construction.

The advantages of the invention are manifest. The device can be constructed of sheet metal by stamping and at an extremely economical cost. There are no moving parts to get out of order and the device is extremely positive and effective to hold the sash in position. The sash can be easily and quickly applied to and removed from the hanger. The hanger will support any of the different types of sash now in general use. When the sash are removed there is no structure entering the space of the room in which the sash are supported which will interfere with walking beneath the hangers.

Changes in the specific form of my invention, as herein described, may be made within the scope of what is claimed without departing from the spirit of my invention.

Having described my invention, what I claim as new and desire to protect by Letters Patent is:

1. A sash hanger comprising a support, a plurality of supporting members depending therefrom and each similar in form, said supporting members being spaced from one another to provide openings therebetween for the reception of rails of sashes, said members having at the lower ends of the same rests for engagement with the under surfaces of the rails of the sashes, stops formed on said members and extending upwardly from said rests and on the same sides thereof as said rests, said stops extending for a portion of the height of the members and adapted to engage the rails at the lower portions thereof to limit movement of the sashes along said rests in one direction, the surfaces of said members above said stops on the same side as said stops receding away from the surfaces of said stops, abutments formed on said members on the opposite sides thereof and extending below said support for a portion of the length of said supporting member, said abutments being adapted to engage the rails of the sashes on the opposite sides from those engaged by the stops and limiting movement of the rails along said rests in the opposite direction, the surfaces of said members on the same side as said abutments, receding from said abutments, said receding surfaces forming enlargements of said openings at the lower ends thereof to allow sashes to be inserted angularly into said openings to clear said rests, said stops and abutments holding said sashes in position upon said rests when the sashes hang vertically.

2. A sash hanger comprising a support, a supporting member depending therefrom, a second supporting member depending from said support and spaced from said first named supporting member to form an opening therebetween for the reception of a rail of a sash, a rest extending from the lower end of said first named supporting member and into said opening and adapted to engage the under surface of the rail of the sash, an abutment on the second named supporting member at the upper end of the same and adapted to engage the sash to hold the same applied to said rest, a stop on said first named supporting member adapted to engage the lower portion of the rail of the sash adjacent said rest and to limit movement of said sash along said rest in one direction, said first-named supporting member above said stop receding from said stop, the rail engaging surfaces of said stop and abutment being substantially vertical, the distance between said surfaces being greater than the thickness 75 of the rail of the sash and greater than the dis-

tance between the end of the rest and the line of said abutment.

3. A sash hanger comprising a support, a supporting member depending therefrom, a second supporting member depending from said support and spaced from said first named supporting member to form an opening therebetween for the reception of a rail of a sash, a rest extending from the lower end of said first named supporting member and into said opening and adapted to engage the under surface of the rail of the sash, an abutment on the second named supporting member at the upper end of the same and adapted to engage the sash to hold the same applied to said rest, a stop on said first named supporting member adapted to engage the rail of the sash adjacent said rest and to limit movement of said sash along said rest in one direction, the rail engaging surfaces of said stop and abutment being substantially vertical, the distance between said surfaces being greater than the thickness of the rail of the sash and greater than the distance between the end of the rest and the line of said abutment, the upper portion of said first named supporting member having a surface lying in continuation of the rail engaging surface of said stop, and above the same receding from the rail engaging surface of said stop and the lower portion of said second supporting member having a surface lying in continuation of the engaging surface of said abutment below the same and receding from the engaging surface of said abutment to form at the ends of said opening enlargements accommodating angular insertion of the sash into said opening to clear the rest.

4. A sash hanger comprising a support, supporting means depending therefrom, said supporting means including a laterally extending rest adapted to engage the under surface of a rail of a sash, said supporting means further including a stop extending upwardly from said rest and spaced from the end of the rest, said stop being adapted to engage said rail on one side and limit movement of the sash in one direction along said rest, abutment means depending from said support and horizontally spaced from said rest to form an opening therebetween for the reception of said rail of the sash when the

sash is arranged in a vertical position, the lower end of said abutment means receding in a direction away from said rest and the upper portion of said supporting means receding away from the upper part of said stop and in the opposite direction to accommodate insertion of the sash angularly into the space between said supporting means and abutment means for the purpose of clearing said rest.

5. A sash hanger comprising a support, supporting means depending therefrom, said supporting means including a rest extending generally in a horizontal direction and adapted to engage the under surface of a rail of a sash, said supporting means further including a stop having a surface disposed above said rest and spaced from the end thereof, said stop surface being adapted to engage the lower portion of said rail on one side thereof and limit movement of the sash in one direction along said rest, said supporting means above said stop receding away from said stop, abutment means depending from said support and horizontally spaced from said stop a distance to receive said rail therebetween when the sash is arranged in vertical position, said abutment means having a surface adapted to engage the rail of the sash on the opposite side of the same and limit movement of the sash in the opposite direction, the distance between the end of said rest and a vertical plane containing the portion of said surface of said abutment means nearest said supporting means being less than the thickness of said rail of the sash to hold the sash in place upon said rest when the sash is arranged in vertical position.
